UNITED STATES PATENT OFFICE

JOSEPH N. HOBART, OF NEW CUMBERLAND, PENNSYLVANIA, ASSIGNOR TO HOLMES
B. GRONINGER, OF PORT ROYAL, PENNSYLVANIA

RAILROAD TIE

Original application filed November 25, 1930, Serial No. 497,968, now Patent No. 1,824,778, dated September 29, 1931. Divided and this application filed July 3, 1931. Serial No. 548,515.

This invention relates to reinforced concrete sleepers or railroad ties, and the present application constitutes a division of my application for patent Serial No. 497,968, filed November 25, 1930, upon which application Patent No. 1,824,778 was granted September 29th, 1931.

It is realized that, broadly, reinforced concrete sleepers are not new, but my invention is directed to certain refinements in structure. One object is to provide a concrete sleeper which has a metallic reinforcement arranged in a particularly effective manner within its body, to the end that in service a tie of given dimensions shall have greater strength to withstand impact of heavy loads. Another object of the invention is to provide a concrete sleeper which is reinforced with strips of metal fabric, which strips of metal fabric are so disposed within the body of the sleeper that a maximum strength is obtained by the use of a minimum weight of reinforcing metal.

In the accompanying drawing Fig. I is a view, partly in side elevation and partly in vertical section, of a sleeper embodying the invention; Fig. II is a view in plan from above of the same; and Fig. III is a fragmentary view in side elevation, and to larger scale, of a typical form of metal fabric which may be employed as the reinforcement for the sleeper.

The sleeper comprises a monolithic body A of elongate, rectangular shape. As indicated in the drawing, it is formed of concrete and has embedded in its body a metallic reinforcement. Advantageously, such reinforcement includes strips 1 of metal fabric, and a plurality of rods 2. Each strip 1, in the plane of its reach, extends with the length and height of the body A; the several strips are disposed at intervals throughout the width of the sleeper, and rods 2 are included, as elements of the reinforcement, with the strips of metal fabric. These rods are located between the strips 1 in the manner illustrated in Fig. II, and it will be seen that, conveniently, there are four rods 2 distributed transversely of the sleeper. The two inner rods of the four extend adjacent the

bottom of the sleeper, while the two outer rods are so bent or shaped with respect to their length that their central portions lie close to the top face of the body A, and their end portions lie adjacent the bottom face of such body. The structural characteristics of these reinforcing members and their organization within the concrete body are factors of prime importance in producing the sleeper of my invention—a sleeper which to the best of my knowledge has greater durability and greater load-carrying capacity than any concrete sleeper of hitherto known construction.

The use of strips of metal fabric, or of expanded metal plate, is particularly desirable. I show in Fig. III a typical form of metal fabric or lattice which is inexpensively formed by the slitting and expanding of a metal plate. The practice followed in so forming such lattice is well known to the art, and I shall not dwell further upon it. It should be mentioned, however, that a fabric having the diamond shaped interstices, as shown in Fig. III, is particularly effective.

As means for securing the rails 14 to the sleeper, I show bolts 13. A tie-plate 11 is positioned beneath each rail, and advantageously I provide a plate 9 of insulating material beneath each tie-plate. Conveniently the sleeper is formed with a shallow pocket 90 for the reception and positioning of each insulating plate 9. Holes 15 extend into the body of the sleeper for reception of the rail-securing bolts 13. In alignment with each bolt hole 15 is a recess or well 3, and within each recess a bolt-securing nut 5 is positioned. The wells 3 are flat-walled, to prevent the nuts housed therein from turning; conveniently the wells are square in cross section and the nuts 5 which they house, correspondingly, are square. It will be noted that each nut 5 is located within the body A, occupying only a portion of its associated recess 3. The remaining portion of the recess—the region of the recess which is unoccupied by the nut—is packed with mastic filler 4, or other suitable filler material which is waterproof and electrically non-conductive. The filler 4 is tightly packed into place, and in

effect makes each nut 5 an integral part of the sleeper. Accordingly, the threaded shank of the rail-securing bolts 13 can be readily screwed home, to secure the rail 5 clamping members 12. As described in my above-noted patent the walls of bolt holes 15 and the walls of the recesses 3 are provided with a lining of insulating material, whereby, the rails are insulated from each other, and 10 are prevented from grounding.

Sleepers which are reinforced in accordance with my invention are compact, providing a more stable track, better rail alignment, and superior track surface.

15 I claim as my invention:

1. A sleeper comprising a monolithic body of concrete having a metallic reinforcement which includes strips of metal lattice cut to size and disposed to extend in the planes of 20 their reaches with the length and height of said monolithic body, which strips are disposed at intervals transversely of said body.
2. A sleeper comprising a monolithic body of concrete having a reinforcement which includes a plurality of strips of metal fabric, which strips of metal fabric are made to size and are disposed to extend in the planes of their reaches with the length and height of 25 said monolithic body and at intervals from one another transversely of the sleeper, and a plurality of rods extending with the length of said body and in the intervals between said strips.
3. A sleeper comprising a monolithic body 30 having a metallic reinforcement which includes a plurality of strips of metal lattice disposed at intervals substantially throughout the width of said body, which strips of metal lattice extend in the planes of their reaches with the length and height of said body, and a plurality of rods extending with 35 the length of said body and in the intervals between said lattice strips, and at least one of said rods being so shaped with respect to its length that its medial portion extends in 40 proximity to the top face of said body, while a remaining portion thereof is located in proximity to the bottom face of said body.

In testimony whereof I have hereunto set 45 my hand.

JOSEPH N. HOBART.
